UNITED STATES PATENT OFFICE.

FRANK. CHASE, OF BOSTON, MASSACHUSETTS.

MACHINE FOR UNITING THE SOLES AND UPPERS OF BOOTS AND SHOES.

SPECIFICATION forming part of Letters Patent No. 293,147, dated February 5, 1884.

Application filed December 1, 1883. (No model.)

To all whom it may concern:

Be it known that I, FRANK. CHASE, of Boston, in the county of Suffolk and State of Massachusetts, have invented certain new and useful Improvements in Machines for Uniting the Soles and Uppers of Boots and Shoes, of which the following is a specification.

In another application for Letters Patent, filed September 17, 1883, and bearing the serial number 106,686, I have described and claimed a method of uniting the uppers and soles of boots and shoes, which consists in forming holes in the parts to be united by punching out or removing portions of the same, and then forcing the removed portions or cores back into the holes, carrying with them the cord or thread previously laid over or across said soles, thus forming a continuous line of fastenings.

My present invention is directed to a machine which is adapted to perform the above-named series of operations; and it is characterized mainly by the combination, with a punch and a driver, of a cord or thread guide arranged and operating automatically and at the proper times, on the one hand, to remove the thread from the path of movement of the punch, so as to permit the latter to punch out from the parts the requisite core or plug; and, on the other hand, to present the thread over the hole thus formed to the driver, which, in its descent, forces the core or plug out from the punch upon the thread and down into the hole.

The nature of my invention and the manner in which it is or may be carried into effect will be readily understood by reference to the accompanying drawings, in which—

Figure 1 is a side elevation of a machine embodying my improvements. Fig. 2 is a front elevation of the upper part of the machine on an enlarged scale, the head which carries the punch, &c., being shown in vertical section. Fig. 3 is a plan of the thread-guide detached. Fig. 4 is a plan of the lever by which said guide is operated.

A is the frame or goose-neck which supports the working parts.

B is a head, which carries the punch, driver, and automatically-operating thread-guide, and which is attached to the front of the goose-neck A. The head is preferably connected to A by

a pin or trunnion, a, which will permit it to oscillate slightly, so as to adapt itself to the movements of the vibratory levers which operate the punch and driver.

C is the punch, which is tubular, and is connected to a tubular stock or stem, C'. The latter fits and is adapted to slide up and down in the head A. Within the punch and punch-stock is the driver D, of a diameter to pass through the tubular punch, and the driver-stock D', which takes its bearing and is adapted to slide up and down in the tubular punch-stock.

Motion is transmitted to the various parts from a driving-shaft, E, supported in bearings in the goose-neck A, on the front end of which shaft is the cam-disk E', provided with a cam-path, b, (seen in dotted lines in Fig. 2,) which is entered by studs c d on the driver-operating lever F and punch-operating lever G, respectively.

F is a bell-crank or elbow lever pivoted at e to the frame of the machine, and connected by a link, f, to the upper end of the driver-stock D', which latter passes out through the upper end of the punch-stock, and also through the punch-operating lever G. Lever G is a straight lever, pivoted to the frame at g, and connected by ball-and-socket or equivalent joint, h, to the top of the punch-stock C'. Inasmuch as it is requisite that the punch should make a deeper cut in some portions of the shoe than in others—for instance, in that portion where it goes through the heel-stiffener before reaching the insole—I make its fulcrum-pin g adjustable up and down, for which purpose the pin g, on which the lever G turns, is eccentric to the stem or hub g', which turns in the frame. On the end of hub g' is a handle, g'', by means of which the hub can be rotated so as to set g up or down, as desired. The fulcrum-pin can be held in its adjusted position by means of a suitable clamp or retaining device, which I have not deemed it necessary to represent, inasmuch as such devices are well known to the skilled mechanic.

The thread-guide hereinbefore mentioned can be made in various ways. One convenient form of such device is shown in the drawings. It consists of a small pinion, i, which lies in a case or chamber of proper form in the base of the head B, and is provided in its cen-

ter with a hole, i' , of proper size and form to permit the passage of the punch. This pinion is provided with an eye or aperture, i^2 , for the passage of the thread or cord x , which latter passes from a bobbin or spool on the frame 5 A, through an eye or opening in the head B, down through the aperture i^2 in the pinion, and thence down and out through the opening j in the bottom of the head. The thread-guide 10 pinion i is operated by a pinion, k , also seated in the base of the head B. The pinion last named is actuated by a vertical spindle, l , whose squared lower end enters a similarly-shaped socket in the pinion, and whose upper 15 portion, which is of angular cross-section, and at the proper point has a quarter twist or turn, l' , passes through an opening or eye, m , of shape corresponding to the cross-section of the spindle in the outer overhanging end of 20 the driver-actuating lever F. When the machine is in operation, the lever, as it passes up and down over the turn l' , will rotate the spindle a quarter-revolution alternately in opposite directions, which will impart corresponding movements to the thread-guide pinion i . The normal position of the pinion is such that its thread-eye i^2 occupies a position in which the thread from it will pass across 25 directly below and in the path of movement of the punch or driver. A quarter-turn of the pinion from this position will carry the thread out of or to one side of the path of movement, so that by alternating movements of the pinion the thread will be thrown into and out 30 of the path of the driver and punch. 35

In connection with the parts of the machine thus far described I employ in practice a jack, Y, on which the lasted boot or shoe Y' is presented.

40 The parts are so arranged and timed in their movements that when the machine is in motion they operate as follows: When the parts are in the position shown in Figs. 2 and 3, the thread-guide pinion is so placed that the thread 45 is to one side of the path of the punch. When the driving-shaft is put in motion, the cam-disk revolving in the direction of the arrow in Fig. 2, first the punch descends, punches out from the work Y the core or plug, and 50 rises, carrying with it said plug, the pinion i makes a quarter-turn, so as to bring the thread across the hole thus made in the work, and the driver descends and forces the plug out from the punch upon the overlaid thread and forces 55 both plug and thread down into the work into the hole cut by the punch. The driver then rises, the thread-guide pinion makes a quarter-

turn in the direction requisite to carry the thread to one side of the path of the punch, the work is fed along, and the series of operations just described are repeated in order stated.

With a view to causing the thread to "tail" to one side or the other, according to the direction in which the last may be moved, I 65 form the eye m in a hub or block, m' , provided with a handle, m^2 , and so mounted in the end of lever F as to be capable of rotating therein, a spring-catch of any suitable construction being provided for the purpose of locking it in 70 position at each half-revolution. In order to make the thread tail in the opposite direction from that shown in Fig. 3, the hub m' should be given a half-turn, thus giving a half-turn to the guide-pinion i . 75

Having described my improvements and the manner in which the same are or may be carried into effect, what I claim as new and of my invention is—

1. The combination, with the punch and the 80 driver, of the cord or thread guide arranged and operating automatically and at the proper times to remove the thread from the path of the punch and to present it to the driver, substantially as and for the purposes hereinbefore 85 set forth.

2. The tubular punch, and the driver arranged within the punch, and operating to expel therefrom the core or plug cut out from the work, in combination with the thread-guide 90 and thread-guide-operating mechanism, whereby the said guide is operated alternately to carry the thread out of the path of the descending punch and into the path of the descending driver, substantially as and for the purposes 95 hereinbefore set forth.

3. The combination, with the punch and punch-stock, of the punch-actuating lever supported upon a fulcrum adjustable for the purpose of varying the depth of cut made by 100 the punch, substantially as hereinbefore set forth.

4. The reciprocating tubular punch, the independent reciprocating driver contained in said punch, and the thread-guide, in combination with the head B, swiveled to the frame of the machine, substantially as and for the purposes hereinbefore set forth. 105

In testimony whereof I have hereunto set my hand this 14th day of November, 1883.

FRANK. CHASE.
